US00D582117S

(12) **United States Design Patent** (10) **Patent No.:** **US D582,117 S**
Chafe et al. (45) **Date of Patent:** **** Dec. 2, 2008**

(54) **CONTAINER**

(75) Inventors: **Adam J. Chafe**, Hudson, OH (US); **Stuart F. Bedford**, Hudson, OH (US); **Kenneth W. Erdmann**, Chagrin Falls, OH (US); **James E. MacDonald**, Medina, OH (US); **Dilip R. Tamhane**, Avon Lake, OH (US); **Oliver J. Ramsey**, Brunswick, OH (US); **Ronald D. Hudas**, Massillon, OH (US); **Charlie Watling**, Raleigh, NC (US); **Forrest A. Burney**, Raleigh, NC (US); **Bob Bruno**, Avon, CT (US); **Scott Belliveau**, Plainfield, IL (US)

(73) Assignee: **The Sherwin-Williams Company**, Cleveland, OH (US)

(**) Term: **14 Years**

(21) Appl. No.: **29/220,702**

(22) Filed: **Jan. 5, 2005**

(51) **LOC (8) Cl.** **07-07**

(52) **U.S. Cl.** **D32/53.1**

(58) **Field of Classification Search** D32/53.1, D32/53, 54; 222/570; 220/570, 757, 754, 220/697, 507, 695, 793, 571, 571.1; 15/257.05, 15/257.06; 206/216; D3/276, 304

See application file for complete search history.

(57) **CLAIM**

The ornamental design for a container, as shown and described.

DESCRIPTION

FIG. 1 is a top perspective view of a container of the present invention.

FIG. 2 is a bottom perspective view of a container.

FIG. 3 is a top plan view of a container.

FIG. 4 is a side elevation view of a container.

FIG. 5 is a front elevation view of a container.

FIG. 6 is bottom plan view of a container; and,

FIG. 7 is a back elevation view of a container.

1 Claim, 4 Drawing Sheets
